UNITED STATES PATENT OFFICE.

WILLIAM E. SHORE, OF NEW YORK, N. Y.

ELECTRICAL PLUG CONNECTER.

Application filed April 4, 1921. Serial No. 458,387.

To all whom it may concern:

Be it known that I, WILLIAM E. SHORE, a subject of the King of Great Britain, and resident of the city of New York, State of New York, in the United States of America, have invented certain new and useful Improvements in Electrical Plug Connecters, described in the following specification and illustrated in the accompanying drawings, 10 that form part of the same.

The principal objects of the invention are, to facilitate the attachment and removal of electrical devices to screw socket connections enabling the connection being placed 15 or removed with ease and rapidity and to eliminate the dangers and losses due to the screwing of plugs into the sockets.

A further object is to dispense with the two piece plug connector while maintaining 20 the essential feature of a rapid breaking of the electrical connection to avoid arcing.

The principal feature of the invention consists in the novel construction and arrangement of parts whereby a plurality of 25 thread engaging members are expanded and locked in the socket or are collapsed to release the plug by a longitudinally slidable member.

In the drawings, Figure 1 is a perspective 30 view of my improved plug shown ready for insertion into a socket.

Figure 2 is an end view.

Figure 3 is a longitudinal sectional view 35 through the line 3—3 of Figure 2 showing the plug secured in a socket.

Figure 4 is a longitudinal sectional view similar to Figure 3 showing the plug collapsed.

Figure 5 is a longitudinal sectional view 40 through the line 5—5 of Figure 2.

Figure 6 is a perspective detail of the expandible member and the sleeve for expanding same.

In the form of the device herein shown the 45 plug centre 1 which may be of any suitable insulating material is substantially cylindrical and is formed with the longitudinal grooves 2, preferably four in number and arranged in diametrically opposite pairs 50 though any desirable number may be used.

A sheet metal sleeve 3 slidably encircles the plug centre 1 and is formed with longitudinal grooves 4 in the periphery which 55 form the inwardly projecting ribs 5. These ribs are a loose sliding fit in the grooves 2 and the upper extremities 6 of the ribs are

drawn inwardly presenting beveled surfaces. The lower end of the sleeve is formed with a laterally projecting flange 7 which is cut away opposite the grooves 4 forming radial 60 slots 8.

A pair of sheet metal discs 9 and 10 are secured to the bottom end of the plug centre 1 by the screws 11 and 12 and each is provided with a pair of spring fingers 13 extending substantially at right angles and parallel with the side of the centre 1. These fingers are bent inwardly at 14 substantially midway of their length and the upper ends 15 are curved transversely and formed with 70 transverse thread corrugations to fit the thread of the standard threaded lamp socket.

The fingers 13 normally spring inward to fit loosely in the longitudinal grooves 2 in the plug centre and when in this position 75 the threaded corrugations 15 have a lesser external diameter than the internal diameter of the thread of the socket shell into which the plug is to be placed, so that the plug will enter freely with a straight insertion. 80

The inturned extremities 6 of the sleeve 85 grooves 4 are adapted upon the outward movement of the sleeve to enter behind the free threaded ends of the spring fingers 13 and expand them outwardly so that their grooved peripheral surfaces correspond with the peripheral diameters of the threaded 90 socket shell and fit the same tightly, said threaded ends sliding in the grooves 4 of the sleeve which thus hold them from lateral displacement. The flanges 7 of the sleeve 95 3 are secured in a cup-shaped member 16 of insulating material which is formed with longitudinal grooves 17 to receive the base ends of the fingers 13 as the cut is moved outwardly to expand the free ends of the fingers 13.

The cup member 16 is provided with a central opening 18 through which the electric wires 19 extend. The discs 9 and 10 are 100 provided with a central hole 20 and the plug centre 1 is formed with a central opening 21 and an eccentrically arranged hole 22 extending through to the outer end.

A central electric contact 23 is secured by 105 a screw 24 to the outer end of the plug centre and is preferably formed with a flexible outer portion 25 extending over the screw. One of the electric wires extends through the hole 22 and is secured to the contact 23 110 and the other wire is connected to a contact 26 connected to the spring fingers 13 by the

screw 11. The outer and central electrical contacts are thus established.

In the use of this device the plug centre is normally extended from the cup 16 as shown 5 in Figures 1, 4 and 5, its outward movement being limited by the base of the fingers 13 engaging the bottom of the sleeve 3. In this position the outer threaded ends of the spring fingers 13 rest within the grooves 2 10 being fully collapsed.

The plug is inserted into the socket with a straight push and when the central contact 23 engages the centre contact of the socket the movement of the plug is arrested 15 but the cup and sleeve will continue to move inwardly. The beveled surfaces 6 of the sleeve engage the fingers 13 expanding them outwardly to engage the threaded surface of the socket and they are then locked 20 securely in place by the presence of the sleeve behind them and the connection holds securely against any pull upon the wire.

The spring contact 23 at the end of the plug is desirable in order to allow the 25 threads of the fingers 13 to seat properly in the shell and to avoid undue pressure being exerted in securing the plug in the socket.

When it is desired to remove the plug it 30 it merely necessary to pull upon the cup member 16. This draws the sleeve 3, which has no binding action but slips freely, from behind the fingers 13, but they are not released until the sleeve clears them when of 35 their own spring quality they withdraw into the longitudinal grooves in the plug centre, thus freeing the plug and it pulls straight out of the socket. A quick break of the electrical contact is thus made simultaneously 40 at both centre and outer contacts by the simple action of pulling upon the cup member 16 and the danger of arcing is eliminated.

An electric plug connection as herein described is extremely simple in its construction and as it eliminates the necessity of the 45 use of a separate plug cap while retaining all the advantages thereof, it may be produced at a lesser cost than the articles at present so commonly used. It will be noted 50 that the wires are not connected to the oper-

ating cup member, consequently pulling on the wire to break the connections, which is one of the most frequent sources of trouble, is eliminated.

What I claim as my invention is:—

1. An electric plug connector, comprising a central insulating member having longitudinal grooves in the periphery, a plurality of spring fingers normally resting in said grooves and having thread corrugations, and means external to the central insulating member 55 slide longitudinally in said grooves adapted to engage in sliding contact with said spring fingers to lock said fingers in engagement with the threaded 60 socket.

2. An electric plug connector, comprising, a central insulating member having longitudinal grooves in the periphery, a plurality of spring fingers normally resting in said 70 grooves and rigidly connected at one end to said central member, a cup member encircling said central insulating member having longitudinal grooves in its inner periphery to receive said fingers, and means secured 75 to said cup member and extending into said grooves to spring said fingers outwardly to engage and grip the socket.

3. An electric plug connector, comprising, a central insulating member having longitudinal grooves in the periphery, a plurality of spring fingers normally resting in said 80 grooves and rigidly connected at one end to said central member, a sleeve encircling said central member and having longitudinal 85 grooves forming ribs slidably engaging the grooves in the central member, the grooves in said sleeve being adapted to receive and hold the spring fingers from lateral displacement.

4. An electric plug connector, comprising, a central insulating member, contacts carried thereon adapted to be expanded to engage in locking contact with the socket shell, and a sleeve member movable longitudinally adapted to expand said contacts, said sleeve member being entirely independent of the wire connections to the contacts carried in the central member.

WILLIAM E. SHORE.
